UNITED STATES PATENT OFFICE.

DANIEL M. CUMMINGS, OF ENFIELD, NEW HAMPSHIRE.

STRAW-CUTTER.

SPECIFICATION forming part of Letters Patent No. 293,150, dated February 5, 1884.

Application filed January 20, 1883. (No model.)

To all whom it may concern:

Be it known that I, DANIEL M. CUMMINGS, of Enfield, Grafton county, New Hampshire, have invented certain new and useful Improvements in Machines for Comminuting Straw, of which the following is a specification.

This invention is a machine for comminuting straw and other materials; and it consists in such a combination of parts, hereinafter fully described, as will secure a better feeding of the material and its more thorough division into fragments.

In the drawings, Figure 1 is a sectional elevation of my improved machine. Fig. 2 is a plan view of a feed-roll. Fig. 3 is a detached view of the feed devices. Fig. 4 is a detached view of one section of the cutter. Fig. 5 is a side view of the cutter detached from the frame.

20 The frame A of the machine supports the shaft *a* of the cutter D, which preferably consists of a series of spiral cutting-knives, *c*, secured to the shaft *a*, all as hereinafter described.

25 At a point above the shaft *a*, and adjacent to the cutter, is arranged a cutter-blade, *E*, bolted to the cross-bar *F* of the frame, and so adjusted that the edges of the saws or knives will shear against the edge of the cutter-blade.

30 At the rear of the blade *E* turns a feed-roll, *G*, above which is a frame, *J*, swinging freely upon extensions of the shaft *a*, and carrying two rolls, *H L*, the shafts of which are connected by a chain belt, *t*, so that the rolls will turn together. The roll *H* is driven by bevel-gears *u* from a shaft, *N*, turning in bearings on the frame *J*, and carrying a worm-wheel, *s*, that engages with a worm, *g*, upon the shaft *a*. By this arrangement the shaft *N* is driven, 40 whatever may be the angle assumed by the frame *J*. The roll *H* has a surface made of ribs in sections, arranged spirally at an angle to form zigzag flutes, as shown in Fig. 2, which insures a better hold upon the straw 45 or other material to be comminuted and a better feeding effect. The roll *L* is a binding-roll, which holds the material down upon the cutter-plate *E* and condenses it in front of the cutter-cylinder, thereby insuring a better 50 cutting effect. A chute, *P*, arranged below the cutter *D* and roll *G*, serves to conduct the particles of material detached by the cutter-

cylinder *D* into the space between two grinding rolls or cylinders *R R'*, rotating in the direction of the arrows, the cylinder *R*, however, turning, by means of the gears shown, at about ten times the speed of the cylinder *R'*. These cylinders are made of stone or metal, or are coated with any suitable facing material, according to the character of the work to be done, and serve to break up or pulverize the chips or slivers formed by the action of the cutting-cylinder *D*, thereby reducing the material to a fine powder or breaking it up into extremely small particles.

It will be apparent that the various shafts may be driven from a main shaft, *h*, which supports the roller *R'*, or in any other suitable manner. The material to be ground may be carried to the feed-rolls through a chute or spout, or may be deposited upon a flat table or platform, *S*.

While any suitable form of cutters may be employed, the cutter I use is a flat spiral blade mounted upon a shaft, and provided with teeth at the edge. This may be made of disks, each bent to impart a spiral shape, as shown in Figs. 4 and 5. These sections, when connected and mounted on the shaft, constitute one blade with a spiral edge, as shown in Fig. 5. This cutting-edge acts on all parts of the material presented to it, and rasps and disintegrates it effectively.

I do not claim a cutter composed of a series of separate disks secured to a shaft, as described in patent to Cummings and Frary, June 13, 1882, No. 259,503, nor, broadly, a spiral cutter, substantially as shown in the patent to S. M. Batty, February 20, 1883, No. 272,403.

I claim—

1. The combination, in a cutting-machine, of a revolving cutter, *D*, and stationary blade *E*, a frame swinging on the cutter-shaft, a feed-roll carried at the outer end of said frame and driven from said shaft, and a pressure-roll carried by said frame at a point above the blade *E*, all as set forth.

2. The combination of the cutter cylinder and shaft, the frame *J*, hung to the shaft and carrying the rollers *L H*, and shaft *N*, gearing with one of the rollers, and worm-gear for driving the shaft *N* from the shaft *a*, substantially as set forth.

3. In a straw-cutter, the combination, with

the stationary cutter-blade E, of the cutter D, consisting of a shaft having a spiral flat blade mounted thereon with teeth at its edge, the said spiral winding in one direction throughout the cutting extent of the shaft, substantially as set forth.

4. The combination of the cutting-cylinder D, cutter-blade E, rollers H L, supported in frame J, as set forth, and the grinding-rolls

R R', geared to rotate at different speeds, substantially as and for the purpose set forth.

In testimony whereof I have signed my name to this specification in the presence of two subscribing witnesses.

DANIEL M. CUMMINGS.

Witnesses:

L. W. CURRIER,

Wm. M. CUSHING.
